His Attorney.

UNITED STATES PATENT OFFICE.

REED J. CAUGHEY, OF SCHENECTADY, NEW YORK, ASSIGNOR TO GENERAL ELECTRIC COMPANY, A CORPORATION OF NEW YORK.

EMERGENCY GOVERNING MECHANISM FOR ELASTIC-FLUID TURBINES AND THE LIKE.

Application filed June 24, 1927. Serial No. 201,248.

The present invention relates to governing mechanisms for elastic fluid turbines or similar machines which governing mechanisms are utilized to effect a shutting off of the supply of actuating fluid to the machine in case of excessive speed. The invention relates especially to governing mechanisms comprising an eccentric spring-restrained weight member carried by the shaft and a trip finger which functions normally to hold the automatically closing emergency valve open, the arrangement being such that when the speed of the turbine or similar machine exceeds a predetermined high value the eccentrically-mounted weight member moves outward under the action of centrifugal force to engage the trip finger, thereby releasing the emergency valve and permitting it to close.

The object of the invention is to provide an improved construction and arrangement whereby a governing mechanism of this type may be tested without overspeeding the machine or without disturbing the initial setting of the emergency governor, and for a consideration of what I believe to be novel and my invention attention is directed to the accompanying description and the claims appended thereto.

In the drawing, Fig. 1 is a sectional view of a governing mechanism embodying the invention; Fig. 2 is a detail view partly in section showing the mechanism of Fig. 1 assembled on a turbine, and Fig. 3 is a plan view of the emergency governor.

Referring to the drawing, 1 indicates an elastic fluid turbine of any suitable type, the turbine being provided with a fluid chest 2 to which elastic fluid is supplied by a conduit 3. In conduit 3 is a combined trip and throttle valve 4, a well-known type being indicated diagrammatically. Valve 4 is biased toward closed position but is held normally open by a catch controlled by link 5 which is connected by a rod 6 to a bell crank lever 7. Connected to the free end of bell crank lever

7 is a plunger rod 8 which extends down through a housing 9 to a point in proximity to a pivoted trip finger 10. Trip finger 10 is provided with a flat surface 11 upon which the lower end of plunger rod 8 normally rests. Fastened on rod 6 is a collar 12 and surrounding rod 6 is a spring 13 which engages collar 12 at one end and a fixed abutment 14 at the other end. Spring 13 acts to force plunger rod 8 downward but is normally held under compression by trip finger 10 upon which the plunger rod rests as is shown in Fig. 2 of the drawing. When trip finger 10 is moved on its pivot from beneath plunger rod 8, spring 13 moves the plunger rod downward, thereby effecting movement of rod 6 toward the left. This moves link 5, thereby releasing the catch for valve 4. Valve 4 then closes automatically, it being biased toward closed position as already pointed out.

The emergency governor comprises a collar 15 fixed on turbine shaft 16 and provided with a guide pin 17 and a guide sleeve 18. Mounted on guide pin 17 and guide sleeve 18 is a governor ring comprising two spaced collars 19 united throughout a portion of their circumference by a plate 20. Diametrically opposite plate 20, collars 19 are connected by a guide sleeve 21 in which guide sleeve 18 slides. The outer end of guide sleeve 21 is arranged to receive an adjustable nut 22. Arranged between adjustable nut 22 and the bottom of the opening in which guide sleeve 18 is fastened is a governor spring 23. The tension of governor spring 23 may be adjusted by means of the nut 22. Guide pin 17 is located in a guide sleeve 24 fastened between collars 19 and on the guide pin is a nut 25 which forms an adjustable stop with which guide sleeve 24 engages. As viewed in Fig. 1 of the drawing, center of the mass of the governor ring is slightly below the center of rotation of the shaft, so that when the shaft is rotating the governor ring tends to move outward against the action of spring 23.

23. Spring 23 is adjusted so that at normal speed it holds the emergency governor ring 5 from moving eccentrically of the shaft far enough to strike trip finger 10. In case of excess speed, however, the emergency governor will move outward sufficiently far to strike the trip finger, thereby effecting closing of valve 4.

The general arrangement of emergency 10 valve and trip mechanism so far described is a known one and operates in a manner well understood by those familiar with this type of apparatus.

As pointed out above, the object of my invention is to provide an improved arrangement whereby the emergency governing mechanism may be tested without overspeeding the machine and without disturbing the setting of the emergency governor. To this 20 end, I provide an emergency governor spring 23 which in operation is stable or under isochronous which means that for every speed of the turbine shaft the governor ring assumes a definite position. I then provide 25 means whereby trip finger 10 may be moved toward and away from the governor ring. In this connection it will be understood that with an arrangement of this type wherein the governor spring 23 is stable, the speed 30 at which the emergency governing mechanism will be tripped will depend upon the distance between the striking surface of the governor ring and the trip finger so that by moving the trip finger toward the governor ring the tripping speed will be decreased while by moving it further from the governor ring the tripping speed will be increased.

In the embodiment of the invention illustrated, housing 9 is made in the form of a 40 cylinder in which is located a piston 26 and between the piston and the head of housing 9 is arranged a spring 27 which normally biases piston 26 toward the bottom of the casting. The outward movement of piston 26 is 45 limited by a guide sleeve and stop 28 and the inward movement of the piston is limited by a shoulder 29. Connected to housing 9 is a pipe 30 through which a liquid such as oil 50 may be supplied to the housing beneath piston 26. In pipe 30 is a suitable two-way control valve 31. On the outer end of piston 26 is a bracket 32 upon which trip finger 10 is pivoted as is indicated at 33. It will thus be seen that the trip finger is carried by piston 26. 34 is a spring which biases trip finger 10 to the position shown in Fig. 1 55 wherein the flat surface 11 of the trip finger is held in engagement with the end of piston 26 and in a position to be engaged by and 60 support the plunger rod 8.

During normal operation, valve 31 is turned to a position to admit fluid under pressure through pipe 30 to the underside of piston 26. This serves to hold the piston in 65 what may be termed its retracted position,

the piston being in engagement with the end of stop 28. As thus positioned, trip finger 10 is spaced sufficiently far from the emergency governor ring that it will be engaged by it only in case the speed of the turbine exceeds a predetermined high value. When it is desired to test the emergency governing mechanism, valve 31 is turned to shut off the supply of fluid to housing 9 and permit the fluid beneath the piston to escape. Spring 27 then forces piston 26 outward until shoulder 29 engages the bottom of housing 9. This moves trip finger 10 sufficiently close to the governor ring that it will be engaged by it and turned to release plunger 8 whereby 70 spring 13 will force rod 6 toward the left as shown in Fig. 2 thereby releasing emergency valve 4, permitting it to close.

After the emergency governor mechanism has operated, valve 31 is turned to again admit fluid under pressure to cylinder 9, thereby 75 moving piston 26 back to its former position. Valve 4 is then reset in the usual way.

With the above described arrangement, it 80 will be seen that the emergency governor mechanism may be tested at any time without overspeeding the turbine, without stopping the turbine and without disturbing the initial setting of the emergency governor 85 spring 23.

In accordance with the provisions of the 90 patent statutes, I have described the principle of operation of my invention, together with the apparatus which I now consider to represent the best embodiment thereof, but I desire to have it understood that the apparatus shown is only illustrative and that the invention 95 may be carried out by other means.

What I claim as new and desire to secure 100 by Letters Patent of the United States, is,—

1. An emergency governing mechanism comprising a spring restrained eccentrically mounted weight member which assumes positions corresponding to the speed of rotation, a trip member adapted to be engaged by said weight member, a piston upon which said trip member is mounted, a cylinder for the piston, 105 stops in the cylinder for limiting the movement of the piston therein in each direction, a spring which biases the piston toward one of said stops, and means for supplying fluid pressure to the cylinder to move the piston into engagement with the other of said stops, whereby movement of the piston from the one position to the other may be effected for adjusting the tripping member relatively to said weight member.

2. The combination with a prime mover having a valve controlling the admission of elastic fluid thereto, of means including a trip element for holding the valve open, an emergency governor comprising an eccentrically-mounted weight member, and a spring which tends to hold the weight member from movement, and means whereby said 110

trip element may be moved toward and away from the weight member while the prime mover is running, said last-named means comprising a movable element upon which the trip element is mounted, a support for the movable element, stops for limiting the movement of the movable element in each direction, means biasing the movable element against one of said stops, and means for moving the movable element against the action of said biasing means and into engagement with the other stop.

In witness whereof, I have hereunto set my hand this 23d day of June, 1927.
